UNITED STATES PATENT OFFICE.

FREDERICK ROETTGES, OF STAMFORD, CONNECTICUT, ASSIGNOR TO WILLIAM R. NOE & SONS, OF NEW YORK, N. Y., A COPARTNERSHIP.

DESIGN FOR A PEDESTAL FOR LIGHTING FIXTURES.

Application filed March 4, 1922. Serial No. 1,039. Term of patent 7 years.

To all whom it may concern:

Be it known that I, FREDERICK ROETTGES, a citizen of the German Republic, residing at Stamford, in the county of Fairfield and State of Connecticut, have invented a new, original, and ornamental Design for a Pedestal for Lighting Fixtures, of which the following is a specification, reference being had to the accompanying drawing, forming part thereof.

The figure is a perspective view of a pedestal for lighting fixtures, showing my new design.

I claim—

The ornamental design for a pedestal for lighting fixtures, as shown.

FREDERICK ROETTGES.
